CLAIM

The ornamental design for an electronic display for a wearable device presenting a graphical user interface, as shown and described.

DESCRIPTION

FIG. 1 is a front view of an electronic display for a wearable device presenting a graphical user interface, showing our new design;

FIG. 2 is an enlarged front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
